CLAIM

The ornamental design for a hand-held radio transmitter, as
shown and described.

DESCRIPTION

FIG. 1 is a perspective view of a first embodiment of a
hand-held radio transmitter of the present invention in which
the left and right sides are mirror images;

FIG. 2 is a perspective view of a second embodiment
thereof;

FIG. 3 is a perspective view of a third embodiment thereof;

FIG. 4 is a perspective view of a fourth embodiment thereof;

FIG. 5 is a perspective view of a fifth embodiment thereof;

FIG. 6 is a perspective view of a sixth embodiment thereof;

FIG. 7 is a perspective view of a seventh embodiment
thereof; and,

FIG. 8 is a perspective view of an eighth embodiment
thereof.
